UNITED STATES PATENT OFFICE.

WILLIAM J. BAUER, OF NEW YORK, N. Y., ASSIGNOR TO NEW YORK STEAM BOILER CLEANER CO. INC., OF NEW YORK, N. Y., A CORPORATION OF NEW YORK.

BOILER-SKIMMER.

1,246,525.

Specification of Letters Patent.

Patented Nov. 13, 1917.

Application filed June 1, 1917. Serial No. 172,169.

To all whom it may concern:

Be it known that I, WILLIAM J. BAUER, a citizen of the United States, and a resident of New York, in the county of New 5 York and State of New York, have invented certain new and useful Improvements in Boiler-Skimmers, of which the following is a specification.

The invention relates to a mechanical 10 skimming device for removing organic or other matter from the water of steam boilers and the like, while the same are in operation, and without in any way interfering with the proper action of said boilers. It 15 is a well-known fact that unless some means or method are employed to remove said matter, a scale soon forms on the flues or tubes and other surfaces on the inside of a boiler, thereby greatly reducing its efficiency 20 and necessitating a shut-down to permit of removal of same. Furthermore, priming difficulties are also met with when the water is not maintained clean; and the boiler will be caused to foam, which will delay the 25 rapidity with which steam may be gotten up. The latter defects are particularly objectionable in connection with locomotive boilers, which are, as a matter of fact, required to be washed out at frequent intervals. The delay in operation and consequent expense and loss is particularly aggravated in case scale has formed, when a locomotive is placed entirely out of commission. 30

It is the object of the present invention to provide a device by which the boiler water may be skimmed or cleaned mechanically, that is to say, without the use of soda-ash or boiler compound, and whereby the 35 frequent washing out of the boiler will be obviated.

The nature of the invention will be best understood when described in connection with the accompanying drawings, in which— 40 Figure 1 is a plan of the improved skimming device as installed in a locomotive type of boiler.

Fig. 2 is a front elevation thereof.

Fig. 3 is a vertical section through the 45 upper portion of the boiler, and of the skimming device, with a portion of the latter removed.

Fig. 4 is a detail sectional view illustrating the manner of adjustably securing the floats.

Fig. 5 is a detail section of a T-connection.

Fig. 6 is an elevation of a T.

Figs. 7 and 8 illustrate a modification.

Similar characters of reference designate 60 corresponding parts throughout the several views.

Referring to Figs. 1 to 4 of the drawings, in which the invention is set forth more particularly in connection with a locomotive type of boiler, 10 designates the boiler and 11 the dry-pipe thereof; and about which latter it is convenient to secure the skimming device hereinafter described. It is, of course, to be understood that this device may be secured in any other suitable manner to some stationary part of the boiler. The said skimming device comprises two yokes or headers 12 and 13 which are secured to the dry-pipe by means of straps 14 65 and nuts 15, or in any other suitable manner, to rigidly hold the skimming mechanism to the boiler. Between the said heads and communicating therewith is a discharge or outlet pipe 16 which is extended through 70 the boiler wall, and communicates, as through a suitable pipe 17, with some suitable discharge point (not shown). The pipe 16 is adapted to receive from the headers 12 and 13 the organic and other matter 75 skimmed from the surfaces of the boiler water (indicated in dotted lines, Fig. 3).

The means to deliver this matter to said headers comprises essentially a skimmer tube, or pair of tubes, 20 upon which are 80 symmetrically mounted pairs of floats 21 of suitable construction. For example, the same may be mounted upon a bracket 22, Fig. 4, provided with oppositely disposed arc-shape sides to which are riveted circular holding bands 23, said bands being adapted to surround the floats and securely hold same, as by means of bolts and nuts 24 which serve to tighten the bands. The bracket 22, moreover, is adjustably mounted 85 relatively to the skimmer tube 20 as by being drilled vertically and having a rod 25 passing therethrough. This rod is preferably made in two parts, as shown, the upper portion of each being semi-circular, and adapted to surround a skimmer tube 20 to 90 which it is secured as by means of bolts and nuts 26, clamping the two members together over said tube. To fix the bracket 22 and thereby the floats 21 carried by same, 95

100

105

110

a set screw or similar device 27 is employed transversely to said rod 25 and bears thereon, as is well understood.

In the locomotive type of boiler herein disclosed, four pairs of floats are shown, two on either side of the outlet pipe 16, the apparatus on one side being a duplicate of that on the other. By means of the adjustment thus afforded, the position of the various 10 pairs of floats, and thereby a plurality of longitudinal slots 28 along both sides of the skimmer tubes, is positively determined with respect to the surface of the water and may be maintained as desired. Furthermore, by 15 means hereinafter disclosed, a pair of floats always maintains a horizontal position irrespective of the rise and fall of the water level in the boiler.

For this purpose, each skimmer tube is 20 mounted to be rotatable about its own axis as well as revoluble about a further axis, or rather a supporting and discharge tube 30 located beneath a said tube 20. The ends of tube 20 are connected to suitable T's 31 25 in such manner as to discharge the matter received by said tubes through a T into short lengths of pipe 32, which in turn are connected to similar T's 33 located near the ends of a supporting or discharge tube 30. 30 To provide for the rotation of a tube 20 about its own axis, there is attached to each end thereof, Fig. 5, a bushing 34 which extends into the T in any well-known or special manner to provide a suitable junction; and between the outlet of the T and the 35 said bushing, there is mounted a plurality of rollers 35 which afford proper bearing for the rotation of said tube 20 in the T. The opposite end of the T 31 may be suitably 40 closed or plugged, and there is attached thereto a roller 36 which is movable with said tube 20, and having its axis of rotation located at right angles thereto. This roller is adapted to ride over the face of an arcuate member 37 secured to a header 12 or 13, or rather to one end of a T 38, Fig. 6. A stop 39 is provided on the arcuate member to limit the extent of oscillation of the roller 36 and thereby of the tube 20, and the said 45 member 37 is adjustable vertically in the T 38, but held against lateral movement by a guide-way 40.

From the T 33, a connection is made to the T 38, in manner similar to the connection hereinbefore described, relatively to tube 20 and T 31. That is to say, tube 30 is also rotatable about its own axis in the T 38 and delivers to the latter the matter collected from the said tube 20. The outlets 60 of the T's 38 communicate through short lengths of pipe 41 with the headers 12 or 13, said lengths 41 also rigidly securing the T's 38 to the said headers. Furthermore, a tube 41 is adjustable vertically in the corresponding header and is held in position

therein by a suitable set screw or the like 42. Thus, a convenient adjustment of the entire apparatus is afforded relatively to the headers and to the boiler itself.

Figs. 7 and 8 illustrate the application of 70 the improved skimmer to a Stirling type of boiler or return tubular boiler. In this case, as a rule, but a single skimmer tube 50 is required with two pairs of floats 51 attached as hereinbefore described, and the guide 75 roller and arcuate guide are omitted. The said skimmer tube 50 is rotatably mounted about a discharge tube 52, as in the previous embodiment; and it is preferred to provide a counterweight 53 for the portion of the 80 structure above the tube 52. To attach the apparatus to a boiler of this type, it is preferred to provide a rod or suitable upright 85 54 which is fixedly secured, in any manner, to the boiler, and to adjustably mount the 90 said apparatus thereon as through lugs 55 and set screws 56. These lugs are respectively attached to the header 57 and to the T 58 at the end of a supporting and discharge tube 52, the entire apparatus being 90 adjustably mounted relatively to a said header 57 as in the previous embodiment.

I claim:

1. A boiler skimmer, comprising: a skimmer tube provided with a plurality of slots 95 to receive the material from the surface of the water of the boiler; floats mounted thereon; a supporting and discharge tube communicating with said skimmer tube, the latter being revoluble about the former and also rotatable on its own axis.

2. A boiler skimmer, comprising: a skimmer tube provided with a plurality of longitudinal slots to receive the material from the surface of the water of the boiler; floats 105 adjustably mounted thereon and movable therewith; a supporting and discharge tube communicating with said skimmer tube, the latter being revoluble about the former and also rotatable on its own axis.

3. A boiler skimmer, comprising: a skimmer tube provided with a plurality of slots to receive the material from the surface of the water of the boiler; floats mounted thereon; a supporting and discharge tube rotatable about its own axis and communicating with said skimmer tube, the latter being revoluble about the former and also rotatable on its own axis.

4. A boiler skimmer, comprising: a rotatable skimmer tube provided with a plurality of slots to receive the material from the surface of the water of the boiler; floats mounted thereon; rollers carried by the ends of said skimmer tube; arcuate members or 120 tracks against which said rollers bear; and a supporting and discharge tube communicating with the said skimmer tube and about which the latter is revoluble.

5. A boiler skimmer, comprising: a ro-

5 tatable skimmer tube provided with a plurality of slots to receive the material from the surface of the water of the boiler; floats mounted thereon; rollers carried by the ends 5 of said skimmer tube; arcuate members or tracks against which said rollers bear; stops on said arcuate members to limit the travel of said rollers; and a supporting and discharge tube communicating with the said 10 skimmer tube and about which the latter is revolvable.

6. A boiler skimmer, comprising: a skimmer tube provided with a plurality of slots to receive the material from the surface of 15 the water of the boiler; floats mounted thereon; means within which the ends of the skimmer tube are rotatably mounted; a supporting and discharge tube about which the 20 said skimmer tube is revolvable; and connections from said means within which the ends of the skimmer tube are mounted to the discharge tube, whereby communication is afforded between said two tubes.

7. A boiler skimmer, comprising: a skimmer tube provided with a plurality of slots to receive the material from the surface of the water of the boiler; floats mounted thereon; means within which the ends of the skimmer tube are rotatably mounted; a supporting and discharge tube about which the 35 skimmer tube is revolvable; means mounted upon said discharge tube and within which the same is rotatable; connections between said last-named means and the means within in which the ends of the skimmer tube are mounted, whereby communication is afforded between said two tubes; and discharge 40 connections from the said means within which the discharge tube is mounted.

8. In a boiler skimmer: a skimmer tube

provided with a plurality of slots to receive the material from the surface of the water of the boiler; floats mounted thereon; a bracket provided with a slot; a clamp member secured about said skimmer tube and 45 having an extension fitting the slot of said bracket; means to secure said extension to said bracket, said bracket being provided with oppositely disposed arc-shape sides; and holding bands secured thereto to retain said floats.

9. The combination with a steam boiler, a plurality of headers, and a discharge pipe therefrom secured to said boiler; of a skimming apparatus, comprising a skimmer tube 55 provided with a plurality of slots to receive the material from the surface of the water of the boiler; floats mounted thereon; and a supporting and discharge tube communicating with the skimmer tube and with said 60 headers, the latter tube being revolvable about the former and also rotatable upon its own axis.

10. The combination with a steam boiler, a plurality of headers, and a discharge pipe 65 therefrom secured to said boiler; of a skimming apparatus adjustably mounted with respect to the said headers, and comprising a skimmer tube provided with a plurality of slots to receive the material from the 70 surface of the water of the boiler; floats mounted thereon; and a supporting and discharge tube communicating with the skimmer tube and with said headers, the latter tube being revolvable about the former 75 and also rotatable upon its own axis.

Signed at New York in the county of New York and State of New York this 29 day of May, A. D. 1917.

WILLIAM J. BAUER.
